(57) **CLAIM**

The ornamental design for a urine collection bag, as shown and described.

DESCRIPTION

FIG. 1 is an isometric view of a urine collection bag illustrating a fill port, a drain port, and a mechanism configured to attach the bag around an appendage, such as a leg of a user, for example, according to one embodiment;

FIG. 2 is a front side view thereof;

FIG. 3 is a back side view thereof;

FIG. 4 is a top side view thereof;

FIG. 5 is a bottom side view thereof;

FIG. 6 is a right side view thereof;

FIG. 7 is a left side view thereof; and,

FIG. 8 is an isometric view of the urine collection bag secured to a leg of a user according to one embodiment.

In FIGS. 3-7 the broken lines illustrating adhesive zones and other secural mechanisms of the urine collection bag depict environmental subject matter only and form no part of the claimed design. In FIGS. 1-6 and 8 the broken lines illustrating a drain port cap/plug of the urine collection bag depict environmental subject matter only and form no part of the claimed design.

The claimed design is broken in two to indicate that no particular length is claimed.
